UNITED STATES PATENT OFFICE.

JOHN F. QUINN, OF COHOES, NEW YORK, ASSIGNOR OF ONE-HALF TO
EMORY J. KINDER, OF BOSTON, MASSACHUSETTS.

DESIGN FOR A SHIRT.

SPECIFICATION forming part of Design No. 23,095, dated March 6, 1894.

Application filed January 23, 1894. Serial No. 497,814. Term of patent 14 years.

To all whom it may concern:

Be it known that I, JOHN F. QUINN, a citizen of the United States, residing at Cohoes, county of Albany, and State of New York, have invented and produced a new and original Design for Shirts, of which the following is a specification, reference being had to the accompanying drawing, showing in a single figure a shirt embodying my new and original design laid out flat, with the shoulder portion opeaed and folded upon the body portion to afford a plan view of the top or shoulder portion.

The shirt comprises the body portion A—, the top or shoulder portion A'— having the neck-opening A²—, the collar portion A³— surrounding the neck opening, and the sleeves A⁴—. The outline of the neck-opening forms a lozenge, or diamond-shaped figure, and the 20 outline of the collar portion A³— forms a po-

lygonal figure inclosing the diamond-shaped figure and having two opposite re-entering angles B—, B—, approaching the inclosed lozenge.

The essential feature of the design is the 25 diamond-shaped neck-opening surrounded by the collar portion having a polygonal outline with re-entering angles on opposite sides of the neck-opening.

What I claim as new, and desire to secure 30 by Letters Patent, is—

The design for a shirt herein shown and described.

In testimony whereof I have hereunto set my hand this 20th day of January, 1894.

JOHN F. QUINN.
